UNITED STATES PATENT OFFICE.

JOHN HARPER, OF KEARNEY, NEW JERSEY.

SHIPPING-BOX.

SPECIFICATION forming part of Letters Patent No. 761,376, dated May 31, 1904.

Application filed December 22, 1903. Serial No. 186,201. (No model.)

To all whom it may concern:

Be it known that I, JOHN HARPER, a subject of the King of Great Britain, residing at Kearney, in the county of Hudson and State of New Jersey, have invented new and useful Improvements in Shipping-Boxes, of which the following is a specification.

This invention relates to shipping-boxes.

The improvements are especially adapted for incorporation into boxes of that kind known to the trade as "drums." Therefore in the present case I will describe the body of the box as being of cylindrical form. Said body, however, may be made of equivalent shapes—for example, it may be elliptical or even square in cross-section—although the cylindrical contour is that which can be made with the best facility.

The improved shipping-box is simple in construction, light, yet thoroughly strong, and can be inexpensively and readily made and when finished can be utilized for a variety of purposes which need not be herein specified.

25 The box-body includes in its make-up board, which may be either mill, strawboard, counter-board, or leather-board, which are various names for practically the same article. The board may be made from other materials, as 30 this feature is not an essential one of the invention.

In the drawings accompanying and forming a part of this specification I have represented one simple embodiment of the device; but I 35 do not limit myself to the showing thus made, for certain variations may be adopted within the scope of my claim succeeding the following description.

In the drawings, Figure 1 is a face view of 40 a sheet or blank from which one portion of the box is to be made. Fig. 2 is a perspective view of the said sheet or blank constructed as hereinbefore set forth and with the ends thereof nearly meeting. Fig. 3 is a sectional 45 elevation of a completed box. Fig. 4 is a horizontal sectional elevation of the same.

Like characters refer to like parts throughout the several figures.

50 In the embodiment of the invention illustrated in the accompanying drawings the body

of the box consists of inner and outer sections, each made from paper-board, the outer section being made from any one of the materials hereinbefore set forth, while the inner section, as will hereinafter appear, is made of 55 pasteboard. Both sections when in finished form are represented as being of cylindrical shape.

The outer section of the box is made from a sheet of material, as 5, (see Fig. 1,) and this 60 sheet is cut to the proper dimensions from suitable stock, the dimensions varying, of course, with the size of the box to be made. This sheet 5 is to be as much longer than the circumference of the finished box as it is desired to have reinforcing bands or hoops, hereinafter described, extend beyond the butt-joint of the ends of said sheet. The outer section of the box of course is to be constructed from the sheet 5, and said outer section 70 has one or more reinforcing bands or hoops, which are made in a simple way. These bands or hoops may be of any desired width, and in the present case they extend along the upper and lower edges of the body. After 75 the sheet has been cut from suitable stock to the requisite size it is incised or scored along its upper and lower portions, as indicated by 6 and 7, the incised lines extending in parallelism throughout the complete length of the 80 sheet, and the incisions extending about half-way through said sheet. After the sheet is incised or scored, as indicated, one end thereof is completely cut out or removed, the cut-out portion being indicated by 8 in Fig. 1 and 85 extending inward from what is shown as the left end of the sheet for the desired distance and from the upper and lower scored lines 6 and 7. The sheet is then doubled or folded on itself along its upper and lower edges, the 90 fold portions being each denoted by 9. (The incising or scoring of the box in the manner indicated renders easy the folding or doubling of the sheet.) The doubled portions are then pressed against what might be considered the 95 outer face of the sheet and may or may not, as desired in particular cases, be cemented thereto. The sheet will now have reinforcing members along its upper and lower edges, and these reinforcing members when the sheet is 100

shaped to the necessary cylindrical form present bands or hoops which completely surround the outer section of the box and thoroughly strengthen said outer section not only 5 as against circumferential strains, but also hold the butt-joint between the ends of the outer section or sheet against opening or bulging apart.

After the sheet is scored, doubled upon itself, and cut out at one end, as indicated, it is 10 connected to a bottom, as 11, which bottom can be readily made from wood, and it is represented as being of circular form and having in what might be considered its upper side 15 a rabbet to receive said outer sheet or section 5. The lower end of the previously-formed reinforcing sheet is introduced into the rabbet, and the lower edge thereof is caused to encircle the vertical wall of the rabbet, the ends of 20 the said sheet being brought into abutment, so as to form a butt-joint.

By forming the sheet 5 in the manner hereinbefore set forth it will be apparent that it 25 presents along its upper and lower edges reinforcing bands or hoops 9, what are shown in Fig. 1 as the left end portions thereof being denoted by 10 and constituting tongues or tabs. When the said ends of the sheet are brought together, these tongues or tabs extend 30 across the butt-joint alluded to and also overlap the adjacent ends of the respective bands or hoops and are cemented or otherwise permanently attached thereto. In each case the bands 9 closely hug the outer section or 35 sheet 5 when the latter is made up into cylindrical form, whereby the box-body is reinforced along its upper and lower edges and whereby the butt-joint mentioned is prevented from being sprung open under ordinary 40 stresses.

When the outer section or sheet 5 is made to conform to the shape of the bottom 11, or, as it might be considered, the lower head of the box, said bottom or lower head and said 45 outer section 5 are rigidly secured together by means of nails, tacks, or other fastenings, which can be driven through the said outer

section and wooden bottom or lower head, respectively, from points outside the box.

The inner section of the box is denoted by 50 12, and it may be conveniently made from pasteboard or cardboard, the sheet of material from which said inner section is formed being approximately the same in length as the inner circumference of the box and in width 55 the same as the distance between the top and bottom of the box or between its two heads. The pasteboard or cardboard sheet 12 adds greater strength to the box and may be glued or otherwise fastened to the outer sheet or 60 section 5. The inner section or sheet 12 corresponds naturally in shape to the outer section; and its ends are brought together to form a butt-joint, which, it will be seen, is out of line with the butt-joint upon the outer 65 section of the box. In fact, the two butt-joints are practically diametrically opposite to each other, so as to give further strength and security. The inner sheet also serves to prevent the escape of the contents of the box 70 therefrom when the box is used for receiving certain kinds of articles. The lower edge of the inner section or sheet 12 rests upon the upper side of the bottom or lower head 11, while its upper edge forms a seat for receiving 75 the upper head or top 13.

Having thus described the invention, what is claimed as new, and desired to be secured by Letters Patent, is—

A box-body having a cylindrical member 80 doubled on itself to form a reinforcing portion, the latter closely hugging the body member, the ends of the latter abutting, and the reinforcing portion extending across the butt-joint, an inner cylindrical section, the ends of 85 which abut, and the two butt-joints being out of line with each other.

In testimony whereof I have hereunto set my hand in presence of two subscribing witnesses.

JOHN HARPER.
